FIG. 3 is a front view thereof shown with the cap in the closed position;
FIG. 4 is a left side view thereof shown with the cap in the closed position;
FIG. 5 is a right side view thereof shown with the cap in the closed position;
FIG. 6 is a back view thereof with the cap in the closed position;
FIG. 7 is a front perspective view thereof shown with the cap in the closed position; and
FIG. 8 is a rear perspective view thereof with the cap in the closed position;
FIG. 9 is a top view of the pouch container according to the first embodiment shown with the cap in an open position;
FIG. 10 is a bottom view thereof shown with the cap in the open position;
FIG. 11 is a front view thereof shown with the cap in the open position;
FIG. 12 is a left side view thereof shown with the cap in the open position;
FIG. 13 is a right side view thereof shown with the cap in the open position;
FIG. 14 is a back view thereof shown with the cap in the open position;
FIG. 15 is a front perspective view thereof shown with the cap in the open position; and
FIG. 16 is a rear perspective view thereof shown with the cap in the open position;
FIG. 17 is a top view of our new design for a pouch container according to a second embodiment shown with the cap in a closed position;
FIG. 18 is a bottom view thereof with the cap in the closed position;
FIG. 19 is a front view thereof shown with the cap in the closed position;
FIG. 20 is a left side view thereof shown with the cap in the closed position;
FIG. 21 is a right side view thereof shown with the cap in the closed position;
FIG. 22 is a back view thereof with the cap in the closed position;
FIG. 23 is a front perspective view thereof shown with the cap in the closed position; and
FIG. 24 is a rear perspective view thereof shown with the cap in the closed position;
FIG. 25 is a top view of the pouch container according to the second embodiment shown with the cap in an open position;
FIG. 26 is a bottom view thereof shown with the cap in the open position;
FIG. 27 is a front view thereof shown with the cap in the open position;

FIG. 28 is a left side view thereof shown with the cap in the open position;

FIG. 29 is a right side view thereof shown with the cap in the open position;

FIG. 30 is a back view thereof shown with the cap in the open position;

FIG. 31 is a front perspective view thereof shown with the cap in the open position; and

FIG. 32 is a rear perspective view thereof shown with the cap in the open position;

FIG. 33 is a top view of our new design for a pouch container according to a third embodiment shown with the cap in a closed position;

FIG. 34 is a bottom view thereof with the cap in the closed position;

FIG. 35 is a front view thereof shown with the cap in the closed position;

FIG. 36 is a left side view thereof shown with the cap in the closed position;

FIG. 37 is a right side view thereof shown with the cap in the closed position;

FIG. 38 is a back view thereof with the cap in the closed position;

FIG. 39 is a front perspective view thereof shown with the cap in the closed position; and

FIG. 40 is a rear perspective view thereof with the cap in the closed position;

FIG. 41 is a top view of the pouch container according to the third embodiment shown with the cap in an open position;

FIG. 42 is a bottom view thereof shown with the cap in the open position;

FIG. 43 is a front view thereof shown with the cap in the open position;

FIG. 44 is a left side view thereof shown with the cap in the open position;

FIG. 45 is a right side view thereof shown with the cap in the open position;

FIG. 46 is a back view thereof shown with the cap in the open position;

FIG. 47 is a front perspective view thereof shown with the cap in the open position; and

FIG. 48 is a rear perspective view thereof shown with the cap in the open position;

FIG. 49 is a top view of our new design for a pouch container according to a fourth embodiment shown with the cap in a closed position;

FIG. 50 is a bottom view thereof with the cap in the closed position;

FIG. 51 is a front view thereof shown with the cap in the closed position;

FIG. 52 is a left side view thereof shown with the cap in the closed position;

FIG. 53 is a right side view thereof shown with the cap in the closed position;

FIG. 54 is a back view thereof with the cap in the closed position;

FIG. 55 is a front perspective view thereof shown with the cap in the closed position; and

FIG. 56 is a rear perspective view thereof with the cap in the closed position;

FIG. 57 is a top view of the pouch container according to the fourth embodiment shown with the cap in an open position;

FIG. 58 is a bottom view thereof shown with the cap in the open position;

FIG. **59** is a front view thereof shown with the cap in the open position;

FIG. **60** is a left side view thereof shown with the cap in the open position;
